CHANGEABLE KEY CYLINDER LOCK

Christian Gabrielsen, Whippany, N.J., assignor to
The Rowe Manufacturing Co., Inc., Whippany,
N.J., a corporation of New York

Application February 21, 1947, Serial No. 730,057

12 Claims. (Cl. 70—385)

1

My invention relates to a changeable key cylinder lock and more particularly to an improved cylinder lock, having a plurality of tumblers, which may be readily, conveniently and expeditiously changed to accommodate a large number of different keys and which operates only on the key to which the lock is set.

In offices and apartments which are let for short periods of time to successive tenants, it is undesirable, from the new tenant's point of view, to retain the former lock on the door to the premises. It is never known with certainty whether the former occupant has distributed keys to employees who might thus be enabled to obtain unauthorized access to the succeeding tenant's premises. This condition frequently necessitates the expensive procedure of removing locks from doors and replacing them. Then, too, the danger of losing keys makes it necessary for a manufacturer to keep large stocks of keys available to fit the locks which he has sold. In many cases when a key is lost and no record has been made of its number, the lock must be destroyed. In the automatic merchandising business where vending machines are employed, it sometimes becomes necessary to change the locks on all of the vending machines owned by an operator due to the circumstance of an employee having been discharged or having left the service of the operator or for the reason that a key is lost, which might enable an unauthorized person to have access to the moneys deposited in such machines. In strong boxes and other locked compartments where for safety's sake the owner desires a key which is under his control alone, it is extremely desirable to provide a lock which may be set to a predetermined key of an unknown and individual contour.

One object of my invention is to provide a cylinder lock which may be readily, simply and conveniently set to operate on a key chosen from any desired number of predetermined contours.

Another object of my invention is to provide a cylinder lock in which the key may be readily changed so that the lock will operate successively to various keys depending on the key to which the lock is set.

Another object of my invention is to provide a lock which is substantially resistant to picking.

Another object of my invention is to provide a lock which when set to a key of a given contour, can be opened only by the key of that contour and cannot be mastered.

Another object of my invention is to provide

2

a cylinder lock of improved and novel construction.

Other and further objects of my invention will appear from the following description.

5 In the accompanying drawings which form part of the instant specification and which are to be read in conjunction therewith and in which like reference numerals are used to indicate like parts in the various views:

10 Figure 1 is a perspective view of a lock showing one embodiment of my invention.

Figure 2 is a sectional view taken on the line 2—2 of Figure 1.

15 Figure 3 is a sectional view taken on the line 3—3 of Figure 2.

Figure 4 is a fragmentary view on an enlarged scale taken on the line 4—4 of Figure 3.

In general my invention contemplates a lock having a cylinder mounted for rotation in a housing. The rotation of the cylinder is adapted to operate a lock bolt. Tumblers comprising slideable plates carried by the cylinder are normally adapted to immobilize the cylinder by coaction with a plurality of adjustable plates carried by the housing corresponding in number to the number of tumblers. The housing plates are mounted for ready adjustment whereby the positions to which the tumblers must be moved to free the cylinder can be readily changed. Upon the insertion of a key of proper contour into the lock, the tumblers will be moved free of the respective housing plates to permit the cylinder to be rotated to operate the bolt immobilized by the lock.

35 More particularly referring now to the drawings, I provide a housing 6 having a pair of wings 8 and 10. The housing is adapted to be closed by a cover plate 12 as can be seen readily by reference to Figures 1 and 2. The housing is formed with a pair of lugs 7 and 9 provided with openings 11 and 13 through which the lock may be secured to a door, cabinet or the like. It is to be understood, however, that any securing means known to the art may be employed. Rotatably mounted within the housing, I provide a cylinder 14 formed with a key slot 16 and a bore 18 formed transversely of the cylinder for the reception of the tumblers 20 and a key guide

22. A retainer bushing 15 is carried by the housing and positions the right-hand side of the cylinder. The end of the cylinder 14 is provided with a pair of tongues 24 and 26 formed integrally therewith. A bolt operating crank 32 is secured to the cylinder tongues 24 and 26

55 by machine screws 28 and 30. A crank pin 34

upon which may be mounted a bushing 36 is carried by the end of the crank 32. The crank pin is adapted to engage the bolt or bolt operating member (not shown) of any appropriate design. The slot 16 in the cylinder and the slot 38 formed in the key guide 22 have the same cross sectional shape and may have any desired form to receive a key 40. The upper contour 42 of the key 40, longitudinally thereof, is complementary to the lower contour 44 of the key. In other words, the distance between the upper contour curve 42 and the lower contour curve 44 is constant and is always substantially equal to the vertical dimension of the opening 46 formed in each of the tumblers 20. This opening can be seen by reference to Figure 3. Each of the tumblers 20, it will be seen, is formed with a central opening, the vertical dimension of which is constant and the horizontal dimension of which is equal to the thickness of the key. Since the tumblers must move up and down, the sides of each of the openings 46 in the tumblers 20 are parallel. Each of the tumblers is provided with an upper projection or lug 48 and a lower projection or lug 50. The tumblers are provided with openings 52 and tumbler spring retaining lugs 54. The tumblers are adapted to be assembled in pairs with a tumbler spring 56 sandwiched between each pair of adjacent tumblers, as can readily be seen by reference to Figure 4. The tumbler spring is hooked underneath the upper retaining lug 54 and over the lower retaining lug 54 of adjacent tumbler plates 20. In this manner, when the key is removed the tumbler spring 56 will move every other tumbler 20 upwardly and every alternate tumbler downwardly. Assembled between the housing 6 and clamped between the housing and the cover plate 12 by means of a pair of screws, 58 and 60, I provide a number of locking plates 62, 63, 64, 66, 68 and 70. Each of the locking plates is provided with an upper wing 76 and a lower wing 78. Each of the wings is formed with slots 74 through which clamping screws 58 and 60 pass. When the screws 58 and 60 are loosened, the locking plates 62, 63, 64, 66, 68 and 70 may be individually moved in a vertical direction through the distance determined by the length of the slots 74. Washers 80 and 82 are provided between the heads of screws 58 and 60 and the cover plate 12. Each of the locking plates is provided with an opening 72. The opening is elliptical in shape and has a minor axis equal to the distance between the top of upper projection 48 and the bottom of lower projection 50. The major axis is equal to at least the minor axis plus the difference between the diameter of the clamping screws 58 and the length of the slot 74 formed in the wing 76 of the locking plates. The dimension of the major axis is not critical and as long as it is at least as large as indicated, the dimension is sufficient. Each of the locking plates 62, 63, 64, 66, 68 and 70 is provided with an upper notch 84 and a lower notch 86 adapted to coact with the locking lugs 48 and 50 carried by the tumblers. In other words, a tumbler 20 may be moved upwardly by the tumbler spring so that lug 48 will be seated in notch 84 or be moved downwardly by the tumbler spring so that lug 50 of the tumbler will be seated in notch 86. In the embodiment I have described, the tumbler springs are assembled so that tumbler plates 20 of the three pairs shown in the drawings are moved downwardly to seat in the lower notches of locking plates 62, 64 and 68 and moved up-

wardly to seat in the upper notches of locking plates 63, 66, and 70. By using a contracting spring instead of an expanding spring, the tumblers may be constrained to move in opposite relative directions, in which case the upper lugs 48 of alternate tumblers will seat in the upper notches of locking plates 62, 64 and 66. In this case the lower lugs 50 of opposite tumblers 20 will seat in the lower notches 86 of locking plates 10 63, 68 and 70.

In operation, the tumblers are brought to unlocked position as shown in Figures 2 and 3 by the insertion of a proper key 40. When this occurs, the cylinder 14 may be turned by the key 15 to the dotted line position shown in Figure 3 thus rotating the crank 32 to operate the bolt moving it to unlocked position. Each pair of lugs 48 and 50 will be free of respective notches 84 and 86 of 20 respective locking plates. When it is desired to change keys, a new key of a different contour is 25 inserted into the cylinder when the cylinder is in unlocked or dotted line position. The screws 58 and 60 are loosened just sufficiently to permit the locking plates to move under camming action 30 of the lugs 48 and 50 against the sides of the openings 72 but not sufficiently to permit the locking plates to move freely about. In other words, it is contemplated that the friction between adjacent locking plates will still remain 35 sufficient under the lessened pressure of the screw so that the plates will retain any position to which they are set. If desired, the lateral surfaces of the locking plate wings may be provided with anti-friction surfaces. The cylinder is rotated by 40 the new key to locked position. During this rotation the lugs 48 and 50 will cam the locking plates either upwardly or downwardly depending on the contour of the key so that each plate is in the position shown in Figure 3. The axis of 45 each plate, it is to be understood, may be displaced one from the other depending on the shape of the key. The screws 58 and 60 are then tightened so that the locking plates are now clamped in their new positions. The washers 80 and 82 50 may be locking washers if desired. The key is then removed and the tumbler springs 56 will move the lugs 48 and 50 of adjacent pairs of tumblers upwardly and downwardly again causing the cylinder to be locked. The old key is now ineffective to operate the cylinder and it can be unlocked only with the new key.

It will be seen that I have accomplished the objects of my invention. I have provided a lock to which the key may be readily changed and 55 which nevertheless is adapted to be opened only in response to a key of a predetermined contour. Due to the overlapping relation of the tumblers and due to the shape of the tumblers, it is substantially impossible to pick my lock. The arrangement, furthermore, is such that a master key cannot be used for a plurality of locks. By means of my lock, offices and apartments may be let to successive tenants and a new key be provided to 60 which the lock may be readily adapted thus avoiding the necessity of changing locks when it is desired to change keys. The old tenants and their privies who might be in possession of former keys are now denied access to the premises. If a key is lost and access can be gained to the office or apartment through another door, the lock may be removed from the inside and readily adapted to a new key without the necessity of 65 destroying the lock.

It will be understood that certain features and sub-combinations are of utility and may be em-

ployed without reference to other features and sub-combinations. This is contemplated by and is within the scope of my claims. It is further obvious that various changes may be made in details within the scope of my claims without departing from the spirit of my invention. It is therefore understood that my invention is not to be limited to the specific details shown and described.

Having thus described my invention, I claim:

1. A lock, including in combination a body member, a cylinder rotatably mounted in said body member, a bore formed in said cylinder extending transversely of its axis of rotation, a plurality of tumblers movably mounted in said bore, a corresponding plurality of locking plates, means for releaseably securing said locking plates to said body member, each of said locking plates being formed with an opening, said cylinder being positioned to extend through the locking plate openings, said tumblers and said plates having coacting inter-engaging portions, biasing means normally urging said coacting portions into engagement whereby to immobilize said cylinder, said tumblers being formed with key engaging means permitting a key of predetermined contour to move said tumblers against the action of said biasing means to free said coacting means whereby said cylinder may be rotated.

2. A lock as in claim 1, including in combination a key guide positioned in said cylinder bore.

3. A lock as in claim 1, including in combination a crank adapted to operate a lock bolt and means for securing said crank to said cylinder.

4. A lock as in claim 1, including in combination a bushing mounted in said body member, said cylinder being mounted for rotation in said bushing.

5. A lock as in claim 1 in which said tumblers comprise plates.

6. A lock as in claim 1, in which said means for securing said locking plates to said body member comprises a cover plate and screw means for moving said cover plate toward said body member whereby to clamp said locking plates in a predetermined position.

7. A lock as in claim 1 in which said body member is formed with a pair of wings, each of said locking plates is formed with a pair of wings, said locking plates being assembled in stacked relation with having their wing portions positioned in the wing portions of said body member.

8. A lock as in claim 1 in which said locking plates are formed with wing portions having slots formed therein, said means for releaseably securing said locking plates comprising clamping screws passing through said slots.

9. A lock as in claim 1 in which said locking plate openings have the cross sectional shape of an ellipse, each of said locking plates being formed with a pair of wings, the minor axis of said ellipses extending in the direction of said wings.

10. A lock as in claim 1 in which said coacting inter-engaging means comprises lugs formed upon said tumblers and re-entrant portions formed in the walls of said locking plate openings.

11. A lock as in claim 1 in which each of said tumblers comprises a plate and said key engaging means comprises openings formed centrally of said plates through which the key is adapted to pass.

12. A lock as in claim 1 in which said biasing means comprises a spring, means for securing one end of said spring to one of a pair of adjacent tumblers and means for securing the other end of said spring to the other of a pair of adjacent tumblers.
